CLAIM

The ornamental design for a sport shoe, as shown and described.

DESCRIPTION

FIG. 1 is a top plan view of a sports shoe showing my new design;

FIG. 2 is a bottom plan view thereof;

FIG. 3 is a left side elevational view thereof; and

FIG. 4 is a left side view thereof;

FIG. 5 is a rear view thereof; and

FIG. 6 an enlarged sectional view of the tongue shown in FIG. 1.
